United States Patent Office.

CHARLES F. MARTINE, OF BOSTON, MASSACHUSETTS.

Design No. 3,018, dated May 5, 1868.

DESIGN FOR A WEATHER-GLASS.

The Schedule referred to in these Letters Patent and making part of the same.

TO ALL WHOM IT MAY CONCERN:

Be it known that I, CHARLES F. MARTINE, of Boston, in the county of Suffolk, and in the State of Massachusetts, have invented a new and useful Design for Weather-Glass; and do hereby declare that the following is a full, clear, and exact description thereof.

This design consists in a stem with a thermometrical scale upon its face, and upon its upper end a semicircular head, upon which a scale is formed, and over which a pointer stands, to indicate the humidity or dryness of the atmosphere. Suitable ornamental brackets, as seen, are placed between the head and the stem.

What I claim as new, and desire to secure by Letters Patent, is—

The design of a weather-glass, substantially as described and shown.

In testimony that I claim the foregoing, I have hereunto set my hand, this 5th day of March, 1868.

CHARLES F. MARTINE.
